(57) **CLAIM**

The ornamental design for the combined ceiling fan housing and light fixture unit, as shown and described.

DESCRIPTION

FIG. 1 is a bottom plan view of the combined ceiling fan housing and light fixture in accordance with my design;

FIG. 2 is an enlarged front view of the combined ceiling fan housing and light fixture unit in accordance with my design;

FIG. 3 is an enlarged top plan view of the combined ceiling fan housing and light fixture in accordance with my design taken along line 3—3 in FIG. 2; and,

FIG. 4 is an enlarged bottom plan view of the combined ceiling fan housing and light fixture unit in accordance with my design.

The front and rear, left and right elevational views are symmetrical.

The broken line showing of environmental structure in FIGS. 1-3 is for illustrative purposes only and forms no part of the claimed design.
